UNITED STATES PATENT OFFICE.

EARL E. BERRY, OF KENNETT SQUARE, PENNSYLVANIA, ASSIGNOR TO AMERICAN ROAD MACHINERY COMPANY, INC., OF KENNETT SQUARE, PENNSYLVANIA, A CORPORATION OF DELAWARE.

SHAKER-SCREEN.

1,344,751.

Specification of Letters Patent. Patented June 29, 1920.

Application filed April 2, 1919. Serial No. 286,949.

To all whom it may concern:

Be it known that I, EARL E. BERRY, a citizen of the United States, residing at Kennett Square, county of Chester, and 5 State of Pennsylvania, have invented a new and useful Improvement in Shaker-Screens, of which the following is a full, clear, and exact description, reference being had to the accompanying drawings, which form a 10 part of this specification.

My invention relates to improvements in shaker screens and has for its object to provide an improved screen, wherein the material for screening will be preliminarily 15 washed to remove any finely divided material and wherein the screens may be arranged in multiple decks without affecting the balance of the machine.

It is known that when screening material 20 through a screen of any mesh, all material finer than the mesh passes through and mixes with the material of the desired size. For example, in screening sand, the material contains very finely divided foreign 25 substances, as loam, which pass through the screen and are mixed with the sand, so that instead of getting clear sand, a mixture of sand and loam is obtained. In my improved type of screen, all of such exceedingly finely divided material may be removed and the sand obtained of a uniform size.

My invention also contemplates the use of multiple decked screens, as, for example, 35 screens of two, three, or four decks, the two upper screens swinging as a unit against the lower one or two screens as a unit, as the case may be. Such an arrangement is found to be most advantageous, but the difference 40 in weight between the upper unit and the lower unit, when two screens swing against one, as in the case of the three-decked type, or because of the difference in weight of the material carried by the two units in the 45 two and four-decked type, causes an unbalanced condition, which throws excessive wear on the power plant and working parts and causes the apparatus to so operate as to render the efficiency of such a construction 50 very low. In my improved type of screen, the screens are placed in perfect balance, so that excessive wear is eliminated and the screen rendered highly efficient.

A preferred embodiment of my invention

is shown in the accompanying drawings, in 55 which—

Figure 1 is a partial plan view of the screen.

Fig. 2 is a side elevation of the screen structure.

Fig. 3 is a side elevation of the connecting rod or pitman connections in a two-decked screen.

Fig. 4 is a side elevation of the pitman connections in a four-decked screen.

Fig. 5 is a cross-section along line 5—5, Fig. 3.

Fig. 6 is a cross-section along line 6—6, Fig. 4.

Fig. 7 is a cross-section of a three-decked 70 screen.

Fig. 8 is a cross-section of a two-decked screen.

Fig. 9 is a cross-section of a four-decked screen.

From the transverse wooden cross-beams *a* depend flexible hangers *b*, to the lower ends of which are bolted opposite ends of transverse angle bars *c*. Near the opposite ends of the angle bars *c* longitudinally extending channel bars *d* are secured. These channels form the sides of the screen proper. The channels *d* forming the sides of the upper or top screen are extended to provide the extensions *e*. To the extensions *e* is 85 bolted a solid bottom *f* provided with the cross cleats *f'*. The screens *g* are bolted to the channels *d*. In the two-decked screen, the screens are hung from the separate hangers and are adapted to work against each other. In the three decked and four-decked screens, the two upper screens hang 90 as a unit and swing together against the lower screen or two lower screens, as the case may be, swinging as a unit. The 95 weights *h* are bolted to the transverse angle bars *c* of the bottom screen.

The connecting or pitman rods are secured to the screens in the following manner: When the connecting rod is fastened to 100 one screen only, as shown in detail in Figs. 3 and 5, an upright gusset plate *i* and angles *k* are bolted to the channel *d*, another angle *k'* being bolted to the top of the gusset plate. The plate *i* and angles *k* and *k'* form 105 a channel in which neatly fits the end of a connecting rod *l*. To the gusset plate is attached a circular steel disk *m* closely fitting

- a recess in the connecting rod. Bolts n draw the rod l to the plate i , one of the bolts extending through the disk m . The disk m acts as a thrust bearing. When the bolts are drawn up for attaching the gusset plate to the connecting rod, the described construction gives a tight fit, eliminating the load from the bolts and avoiding the possibility of the parts coming loose.
- 10 Where the connecting rod is attached to a pair of screens to work them as a unit, as shown in detail in Figs. 4 and 6, the gusset plate o is bolted to the channels d of both screens. The angles k^2 and k^3 are bolted to the plate, and these angles and the plate o form a channel in which the end of the connecting rod l neatly fits. The disk m' fits into a recess in the plate, acting as a thrust bearing, and the bolts n' , one of which extends through the disk m' , draw the rod l to the plate o as above described.
- The connecting rods l are of wood and are tapered down to a small section in the middle so as to give the necessary flexibility.
- 25 The ends of the rods adjacent the crank shaft r are reinforced by top and bottom metal strips p and a metal. The rod is orificed to receive its corresponding crank on the shaft r .
- 30 In operation, the material to be screened is placed on the solid bottom f of the extended portion e of the upper screen. The screens are put in motion and a stream of water applied to the material. The shaking action causes the material to drag over the cleats f' , which, in connection with the stream of water, loosens, by a scrubbing action, any loam or foreign material sticking to the mass.
- 40 The finely divided material, as loam, passes to the bottom and is caught by the cleats f' . The washed material then passes to the first screen g .
- The weights h which are bolted to the
- 45 lower screen compensate the lower unit for the greater weight of the upper unit, thus counterbalancing a lower unit of one screen against an upper unit of two screens, or, as

may be advisable, compensating the lower unit for the greater weight of a similar upper unit arising from the greater quantity of material carried by the upper unit, on the screens and on the extension, wherein the material is preliminarily scrubbed.

Having now fully described my invention, what I claim and desire to protect by Letters Patent is:

1. In a shaker screen, the combination with a plurality of screen sections, one above the other, adapted to be reciprocated as units in opposition to one another, and a counterweight extending transversely of and secured beneath the lowermost screens.
2. In a shaker screen, the combination with a plurality of screens, one above the other, adapted to be reciprocated as units in opposition one to another, an imperforate section lying in the same plane as the uppermost screen and forming an extension thereof, and counterweights secured at intervals to and extending transversely of the lowermost screen.
3. In a shaker screen, the combination with a plurality of sets of screens, one above the other, the screens of a set being adapted to be reciprocated as a unit in opposition to the screens of an adjacent set as a unit, and a counterweight extending substantially across the bottom of the lowest screen and secured thereto.
4. In a shaker screen, the combination with a three-deck screen and means for suspending the same, of a shaft, a connecting rod operable from the shaft and connected with one screen so as to vibrate the same, another connecting rod operable from the shaft and connected with the other two screens to vibrate them in unison, and transversely extending counterweights secured beneath the separately vibratable screen to equalize the weight of the two screens vibrating in unison.

In testimony of which invention, I have hereunto set my hand, at Kennett Square, Pa., on this 27th day of March, 1919.

EARL E. BERRY.
